St. Paul, Minnesota

UNITED STATES PATENT OFFICE.

ARTHUR C. GAYNOR, OF STRATFORD, CONNECTICUT.

HINGE FOR DOOR-PLATES AND OTHER STRUCTURES.

1,378,944.

Specification of Letters Patent. Patented May 24, 1921.

Application filed February 9, 1920. Serial No. 357,474.

To all whom it may concern:

Be it known that I, ARTHUR C. GAYNOR, a citizen of the United States, and a resident of Stratford, county of Fairfield, State of Connecticut, have invented certain new and useful Improvements in Hinges for Door-Plates and other Structures, of which the following is a specification.

This invention is concerned with a method 10 of working metal and also with the product of such method.

One of the objects of the invention is to provide an article of manufacture having a hinged door or cover, as for instance a flush 15 receptacle door plate, which article shall be easy and inexpensive to manufacture and which shall nevertheless be durable and effective in use.

Another object is to provide a method of 20 making an article of the above type which method shall be capable of expeditious execution with relatively simple tools.

Another object is to provide a hinge for an article of the type mentioned which shall 25 be strong, durable, inexpensive, and which shall yet not impair the ornamental appearance of the article.

Other objects will be in part obvious and in part pointed out hereinafter.

The invention accordingly consists in the 30 features of construction, combination of elements, arrangement of parts, and the steps of the method which will be hereinafter set forth and the scope of the application of 35 which will be indicated in the appended claims.

In the accompanying drawings wherein is shown one of various possible embodiments 40 of the several features of this invention, Figure 1 is a face view of an electric flush receptacle door plate, the cover being removed.

Fig. 2 is a rear view of the door plate of Fig. 1 with the cover in place.

Fig. 3 is a longitudinal sectional view taken along the line 3—3 of Fig. 2.

Fig. 4 is a sectional view on an enlarged scale taken along the line 4—4 of Fig. 2.

Fig. 5 is a plan view with parts broken away of a modified embodiment of my invention.

Similar reference characters refer to similar parts throughout the several views of the drawings.

Referring now to the drawings there is

shown a flush receptacle door plate, comprising a sheet metal plate member 1, having preferably a beveled border 2 to create a pleasing appearance. Openings 3 for fastening members are stamped out of the 60 plate as shown.

The door of the plate as shown at 4, preferably constitutes the piece of metal removed from the original plate member to provide the door case 5. By preference the 65 door, and therefore of course its case are generally circular in shape as indicated at 6, there being preferably a rectangular extension 7 at the upper end, terminating in an upper rectilinear edge 15. 70

A hinge is provided for the door preferably comprising a hinge rod 8, passing substantially midway along the rear surface of the extension 7 of the door, said rod being preferably soldered at its ends as at 9 and 10 75 upon the rear of the door plate.

The loop or eye for the hinge is preferably formed as best indicated in Fig. 4. A chisel or similar tool is manipulated to cut a channel 11 in the rear surface of the door in a 80 direction perpendicular to the axis about which the door is to pivot, terminating adjacent said axis. The shaving will automatically coil or curl as it is generated and little or no work beyond clipping off the excess length of the shaving will be required for making the loop or eye of proper size and shape to lodge the hinge rod 8, as shown at 13 in Fig. 4. By preference two loops are thus formed, symmetrically arranged adjacent the sides of the door extension 7 as best shown in Fig. 2. 85

A lip 14 semi-circular in shape is preferably depressed or embossed into the plate member 1 adjacent the door case 6, this lip 90 being preferably diametrically opposite the hinge. This lip as will be apparent serves not only to limit the door to its position within the door case but it also serves to accommodate the finger nail for purposes of 100 opening the door.

It will be seen that contact of the surface of extension 7 against the rectangular upper edge 15 of the door case will limit the opening movement of the door about the hinge 105 rod. Thus the hinge is protected against destruction in use which might occur if the door were free to be opened to an extent limited only by the surface of the plate.

The method of manufacturing the door 110

plate is to blank out the door plate member 1, the door case 6 and the holes 3 preferably in a single blanking operation and by means of a multiple die. Thereupon a forming die may be used to produce the bevel border 2 and the depressed or embossed lip 14. The piece of metal punched out in making the door case as above noted will serve as the door. By preference a chisel is used 10 to make two shavings which are left attached to the door and formed into the loops or eyes 12 in the manner fully described above. The hinge rod 8 is then inserted through the two loops or eyes, the 15 door is placed into the door case in the plate with the rod 8 contacting the rear surface of the plate at its ends, and said ends are thereupon soldered in place upon the door plate, thus completing the manufacture of 20 the article.

It will be seen that I have provided a cheap and expeditious method of manufacturing a novel flush receptacle door plate, which will be durable and effective in use. 25 The loop or eye of the hinge is easily formed as an integral part of the article, thus dispensing with the need for making separate loop pieces and the expense and trouble of soldering, riveting or otherwise applying 30 such elements to the door. Although the loop or eye is formed as an integral part of the door, the door itself remains imperforate and the effectiveness of the door will not be impaired either from an esthetic standpoint or with regard to its utility in keeping out dust or dirt.

Although the loop or eye is preferably formed by the method specifically set forth, it will be understood that other methods 40 may be employed to form a loop or eye as an integral part of a plate without perforating or slitting such plate, and it is to be understood that the broader aspects of that part of my invention bearing on the article of 45 manufacture will embrace substantially the hinge shown in Fig. 4 without regard to what method may be used for manufacturing the same.

It will also be apparent that my method 50 of forming the shavings upon a piece of workable metal and using said shavings to perform a mechanical function, while retaining the same or a portion thereof as an integral part of the plate, is of broader application to the mechanical arts generally and such broader application is within the scope of my invention.

It will also be apparent with regard to my hinge construction that the disposition of 60 the elements may be reversed, the hinge rod being soldered to the door and the loops or eyes being formed upon the door plate. Thus as illustrated in Fig. 5, the hinge rod 8' is soldered to the door at 9' and the ends

of the rod are embraced by loops or eyes 12' 65 formed from shavings cut in the rear surface of the main plate member 1', thus making channels 11'.

It will also be apparent that although I prefer to use two loops or eyes, a greater or 70 lesser number may be employed.

Although the flush receptacle door plate shown is the preferred article of manufacture, it will be understood that other articles of manufacture for different purposes will 75 be embraced within the scope of my invention.

It will thus be seen that there is herein described apparatus and a method in which the several features of this invention are 80 embodied, and which apparatus in its action and which method in its operation attain the various objects of the invention and are well suited to meet the requirements of practical use.

As many changes could be made in the above construction and method and many apparently widely different embodiments of this invention could be made or executed without departing from the scope thereof, it 90 is intended that all matter contained in the above description or shown in the accompanying drawings shall be interpreted as illustrative and not in a limiting sense.

Having thus described my invention what 95 I claim as new and desire to secure by Letters Patent is:

1. A sheet metal plate provided with a door or cover, coöperating hinge elements for said door, one of said hinge elements being rigid with said plate and the other rigid with said door, one of said hinge elements being disposed within the contour of and formed as an integral part of the member on which it is located, said member having a continuous integral surface adjacent to and in substantial alinement with said hinge elements.

2. A sheet metal plate provided with a door or cover, a hinge rod rigidly secured to the surface of one of said members and extending in substantial alinement therewith, a hinge eye extending about said rod, said eye being disposed within the contour of the other of said members, and formed as an integral part of said member, said member having a continuous outer surface adjacent to said eye.

3. A sheet metal flush receptacle door plate comprising a plate member, a door member to fit a corresponding door case in said plate, a hinge rod fixed to said plate and extending in substantial alinement with the surface thereof, and a coöperating hinge eye formed from a shaving cut in one face 120 of said door.

4. A sheet metal flush receptacle door plate, comprising a plate member, a door

- member to fit a substantially identically formed door case in said plate, said door member and said case being circular with a substantially rectangular extension at the 5 hinge end, a hinge rod fixed to said plate and passing midway along said extension and disposed in substantial alinement with the surface thereof, and a pair of hinge eyes coöperating with said rod, said eyes being 10 formed from shavings cut in a face of said door and left as integral parts of said door.
5. A sheet metal flush receptacle door plate comprising a plate member, a door member to fit a substantially identically 15 formed door case in said plate, said door member and said case being circular with a substantially rectangular extension at the hinge end, a hinge rod passing midway along said extension and soldered at its ends 20 to the rear surface of said plate and disposed in alinement therewith, a pair of hinge eyes coöperating with said rod, said eyes being formed from shavings cut in a face of said door.
- 25 6. The method of forming a flush receptacle door plate which consists in stamping the door member out of a plate, cutting a shaving from one face of said door, allowing said shaving to form a loop or eye in- 30 tegral with said door, passing a hinge rod through said eye, inserting said door into the hole formed when the same was stamped out of said plate, and securing the ends of said rod to said plate in substantial aline- 35 ment with the surface thereof.
7. As an article of manufacture, a piece of metal having a shaving curved to form a loop or eye, one end of said shaving being integral with said piece of metal, the other
- end free and lying substantially in the plane 40 of the surface of the said piece of metal.
8. As an article of manufacture, a piece of metal having a shaving from one surface thereof curved to form a loop or eye, one end of said shaving being integral with said 45 piece of metal and the other end terminating near its surface.
9. As an article of manufacture, a flat sheet of metal having a channel in its sur- 50 face, the metal near one end of said chan- nel being bent around to form a loop or eye, the lower surface of said loop or eye coinciding substantially with the surface of the flat sheet.
10. As an article of manufacture, a flat 55 sheet of metal having a channel in its sur- face, the metal near one end of said chan- nel being bent around to form a loop or eye disposed beyond the end of said channel and lying substantially in the plane of the 60 surface of the said flat sheet.
11. An as article of manufacture, a hinge element, consisting of a piece of metal hav- 65 ing an attached shaving from a surface thereof fashioned into the shape of a loop 65 or eye.
12. As an article of manufacture, hinge elements consisting of a piece of metal hav- 70 ing channels in its surface, the metal near one end of each of said channels forming a loop or eye, each loop or eye being secured to the said piece of metal in the same axial line.

In witness whereof I have hereunto set my hand at Bridgeport, county of Fairfield, 75 State of Connecticut, this 5 day of February, 1920.

ARTHUR C. GAYNOR.
